UNITED STATES PATENT OFFICE.

WILBUR L. WRIGHT, OF BALTIMORE, MARYLAND, ASSIGNOR TO THE PAPER VESSELS COMPANY, OF BALTIMORE, MARYLAND, A CORPORATION OF MARYLAND.

WATERPROOFING APPARATUS AND THE LIKE.

1,197,324.

Specification of Letters Patent. Patented Sept. 5, 1916.

Application filed October 30, 1915. Serial No. 58,859.

To all whom it may concern:

Be it known that I, WILBUR L. WRIGHT, a citizen of the United States, and resident of Baltimore, State of Maryland, have invented certain new and useful Improvements in and Relating to Waterproofing Apparatus and the like, of which the following is a specification.

This invention relates to certain improvements in the art of waterproofing paper and like material containers; and the objects and nature of the invention will be readily understood by those skilled in the art in the light of the following explanation of the accompanying drawings illustrating what I now believe to be the preferred embodiments or mechanical expressions from among other forms, constructions and arrangements within the spirit and scope of my invention.

An object of the invention is to provide an improved apparatus for applying waterproofing or other liquid to the exterior and interior surfaces of paper and other containers and for draining surplus liquid from such containers and for approximately drying the surfaces of the containers to which the liquid has been applied, preparatory to the discharge of the waterproofed containers for further treatment or operations.

A further object of the invention is to provide apparatus for spraying liquid on the inner and outer surfaces of paper and the like containers and for removing surplus liquid therefrom in the process of waterproofing or other treatment of paper and other material containers.

A further object of the invention is to provide apparatus for spraying the interior surfaces of paper or like material containers, with waterproofing or other liquid while such containers are maintained in inverted position.

A further object of the invention is to provide means for spraying or approximately atomizing waterproofing liquid and thus producing a cloud or fog of such liquid, and for passing paper containers through such fog or cloud to thoroughly subject the interior and exterior surfaces of such containers to the action of such atomized liquid.

A further object of the invention is to provide apparatus for waterproofing paper

and like material containers and then delivering the same approximately dried and with surplus liquid removed therefrom, for further operations.

A further object of the invention is to provide means for effectively waterproofing paper and like material containers without dipping the same, and without leaving irregular deposits of surplus waterproofing material on portions of the surfaces of the containers.

A further object of the invention is to provide means for simultaneously transporting a multiplicity of paper or like material containers while said containers are being successively subjected to a waterproofing liquid, and while said containers are being drained and dried.

A further object of the invention is to provide improved means whereby paper and like material containers can be uniformly and effectively waterproofed with economy and rapidity.

A further object of the invention is to provide improvements in arrangements of parts and in combinations of elements for the production of a highly advantageous apparatus for waterproofing paper containers and parts.

The invention consists in certain novel features in construction, and in arrangements and combinations as more fully and particularly set forth hereinafter.

Referring to the accompanying drawings: Figure 1, is a perspective view of apparatus embodying my invention. Fig. 2, is a central vertical section thereof. Fig. 3, is a top plan thereof. Fig. 4, is a detail view. Fig. 5, is a vertical section somewhat diagrammatical of a modified arrangement embodying my invention.

In the particular embodiment of my invention illustrated, an approximately closed chamber is provided over and draining into a tank containing a supply of waterproofing liquid. A suitable conveyer is arranged in said chamber, and this conveyer is preferably constantly traveling along an extended path of movement within the chamber and is provided with a multiplicity of brackets, holders, or supports, each adapted to carry a single container in an inverted position so that the conveyer will be capable of simultaneously carrying a large number of containers within said chamber and of con-

stantly advancing the same along said path from a point where the containers are successively placed on the supports to a point where the containers are successively discharged or removed from said supports after having traveled the length of said path within said chamber. Near the beginning of said path of movement means are provided to spray waterproofing liquid over the interior 10 and exterior surfaces of the containers as said containers successively pass said means during the travel of the conveyer. This liquid is drawn from the tank and liquid discharged in said chamber drains or drops 15 back into the tank except where taken up by the surfaces of the containers. The containers after being subjected both exteriorly and internally to the waterproofing liquid move along the extended path within the 20 chamber and surplus liquid is drained therefrom and the liquid on or in the surfaces of the containers sets or dries before said containers are discharged from the chamber.

In the particular embodiment of my invention typified by Fig. 1, of the accompanying drawings, I provide an open top tank or pot 1, adapted to contain the waterproofing liquid and having a hot water, or if desired, steam, heating jacket 2, and any 25 suitable supporting means. However, any suitable means can be provided to maintain the waterproofing liquid in the tank 1, at the desired temperature, and my invention is not limited to the provision of a steam coil 2', 30 in the water jacket 2, to heat the water and consequently the waterproofing material, or to any particular heating means.

In the particular example illustrated, I show paraffin in the tank 1, maintained in 40 the desired liquid condition by heat, but my invention is not limited to the utilization of paraffin as the waterproofing liquid as other liquid might be employed that possesses the capacity of rendering paper or like material approximately water proof when applied thereto. Above this tank I provide a suitable box, inclosure or casing 3, which is formed with a usually contracted central bottom opening coinciding or registering 45 with the top opening of the usually circular tank and surrounded by an annular or continuous depending neck or flange 4, depending into the tank and fitting the inner vertical surface of the upright surrounding wall 50 of the tank, and forming an approximately tight slip joint between the upper end of the tank and the bottom of the casing. It will hence be observed that the interior of the casing forms in effect an enlarged upward 55 continuation of the space within the tank above the liquid level therein, although my invention is not limited to such formation.

The annular floor or bottom wall 5, of the casing preferably flares upwardly and outwardly from the neck or flange 4, so that

liquid dropping or flowing onto said floor, constantly tends to drain therefrom into the tank. The surrounding vertical wall of the casing rises from the outer upper edge of said floor so that liquid will flow down the 70 inner surface of said wall to said floor for return to the tank.

The casing is provided with a top 6, preferably of a conical formation so that liquid and moisture that may collect on the inner 75 surface thereof will tend to drain therefrom to the inner surface of said vertical wall. This top wall or cover preferably embodies one or more removable sector-shaped sections 80', provided with exterior handles 6'', 80 whereby access can be readily gained to the interior of the casing. Within this casing I provide a rotating table or carrier carrying an endless series of more or less closely arranged individual supports for the articles 85 to be waterproofed or otherwise subjected to the liquid from the tank, and this rotary carrier is supported and driven by a vertical rotary shaft 7, arranged approximately centrally within the surrounding vertical wall 90 of the casing and depending loosely through a hole in the center of the top wall of the casing from a top support 8, arranged above the casing. The shaft is carried by this support 8, which is fixed to and upheld by a 95 post 9, or by any other suitable means. The shaft depends through and rotates in this support and at its upper end is fixed to shaft-driving gear 10, arranged on the support. This gear is driven by meshing gear 11, fixed to shaft 12, mounted in suitable boxes carried by the support, although any other suitable means can be provided for driving the rotary table. In the example illustrated, the shaft 12, is operatively connected with and actuated by the driving or power shaft 13, through the medium of a meshing worm and worm gear 14, said power shaft being carried by and mounted in gear box 15, which also incloses the worm 110 gearing. The power can be applied to shaft 13, in any suitable manner, as by a driving belt applied to pulley 16, on said shaft.

In the example illustrated, the rotary table, comprises a center hub 17, fixed to 115 the lower end of the shaft 7, and radiating arms 18, rigid with an annular rim 19, at the outer ends of said arms. The devices for holding the articles to be waterproofed are mounted on this rim. For instance, 120 where paper or like material cans, bottles, or other containers (such as a) are to be waterproofed both internally and externally, I mount a multiplicity of arms or brackets 20, on and uniformly spaced around the 125 circle of this rim, and projecting outwardly and upwardly therefrom so that each bracket can support one container in an inverted position by extending up into the container and engaging the inner surface 130

of the bottom thereof so that the container depends around the bracket and rests on and is virtually suspended from the upper end thereof.

5 Where it is desirable to thus carry the containers in an inverted position and to apply the liquid to the interiors thereof, it is advantageous to provide a container supporting arm or bracket that offers the least 10 possible obstruction to the entrance of the liquid spray to the interior of the container and deposit thereof on the container's inner surfaces. Various forms and arrangements can be provided for this purpose, although I 15 show each bracket comprising an upright length 20, of stiff wire or small metal rod at its lower end 21, bent laterally to a horizontal position and fixed to a block 22, secured to the rim 19. The horizontal portion 21, 20 projects radially from the rim and the length 20, extends upwardly therefrom at a slight outward angle and is preferably of a length at least equal to the inside length of the container so that the upper end of said 25 length will engage the bottom of the container with the lower edge of the container either engaging or slightly elevated from the radial portion 21.

If so desired, the upper portion of each 30 bracket can be provided with laterally projecting bent wire arms 23, braced by wires 24, to engage the vertical inner surface of the container and hold the container in the desired position and against swinging or 35 oscillating on the bracket. It will be noted that the brackets are arranged at an upward outward inclination, so that the containers in assuming a vertical position, will have their lower open ends approximately unob- 40 structed for the free entrance of liquid spray from below.

The table rim 19, is spaced a distance 45 from the vertical surrounding wall of the casing 3, and the brackets 20, are arranged to carry the containers in vertical positions and in a circular path near but spaced from the vertical wall of the casing with their open ends over the space between said rim and said wall and preferably directly above 50 the inclined drainage floor 5, of the casing so that liquid draining from the containers will drop onto said floor. The table is preferably approximately closed between the hub 17, and rim 19, by a floor or plate 25, 55 to form the floor or bottom of the waterproofing and drying chambers hereinafter referred to.

The casing 3, is provided with an opening, such as *b*, in its vertical wall, through 60 which the operator can extend the hand into the casing to supply containers to the rotary table by placing them on the brackets 20, as they successively move past said opening. This opening *b*, virtually establishes the 65 receiving station for the rotary table, or the

front end of the extended path along which the containers travel in the casing. The discharge station for the rotary conveyer (table), or the rear end of said path of movement, is established by an opening *c*, 70 through the vertical wall of the casing, said opening *c*, being usually located comparatively close to the opening *b*, so that said extended path of movement will approximately extend completely around the conveyer or encircle the interior of the casing. 75

A container spraying chamber is provided within the casing immediately in advance of the opening *b*, in the direction of movement of the rotary conveyer, and this chamber is 80 traversed by the path along which the containers travel. This chamber in this example, is shown formed by the vertical partitions or plates 26, radiating approximately from the center of the casing to the vertical 85 wall thereof and extending from the top wall of the casing approximately down to the rotary conveyer and secured to and supported from the top wall. The lower outer corners of these partitions are notched or cut 90 away for the passage of the upright brackets of the conveyer and the containers carried thereby into and from said chamber. Within this chamber I locate spraying and atomizing devices designed and arranged to coat 95 or subject the complete exterior and interior surfaces of each container with or to the action of the liquid discharged by said devices so that when each container leaves said chamber it will be completely coated or im- 100 pregnated both externally and internally with the waterproofing substance. To this end, I arrange a downwardly discharging liquid spraying or atomizing nozzle 28, in said chamber and above the path traveled by 105 the containers to thoroughly subject the upper ends of the containers with the liquid spray; and an upwardly discharging liquid spraying or atomizing nozzle 29, below the path of the containers through the chamber 110 to direct spray up into the containers and thoroughly coat or impregnate the inner surfaces thereof with the liquid; and horizontally discharging and oppositely-arranged liquid spraying and atomizing nozzles 30, 115 31, located at opposite sides of the path of the containers and directing spray radially with respect to the conveyer to thoroughly coat and impregnate the exterior vertical surfaces of the containers with the liquid. 120 These several spraying heads or nozzles are provided with regulating and cut off valves 32, and are supplied with liquid under pressure by branch pipes from the liquid supply pipe 33, forming the discharge pipe of any 125 suitable pump 34, arranged to draw liquid from tank 1, and drive the same under the desired pressure through said pipes to the several nozzles.

In the example illustrated, the pump 34 130

is shown submerged in the liquid in the tank and is actuated by sprocket chain 35, from shaft 36, extending to the exterior of the tank and driven by belt applied to pulley 37.

- 5 The nozzles 31 are usually spaced a distance from the containers toward the center of the casing, while the nozzles 30, are spaced a distance outwardly from the containers beyond the circle in which they travel. The casing is formed with a narrow offset recess or pocket 38, to receive the nozzles 30, and this pocket is usually provided with a removable cover 39, through which access can be gained to said nozzles 28 and 15 29, and the interior of the spraying chamber. Access to the nozzles 31, can be gained through an opening such as 26', in one of the partitions 26, from the interior of the casing on the removal of one of the top sections 6'. The pocket 38, is normally closed, except at its inner end, where the pocket opens directly into the spraying chamber, and the floor of the pocket is preferably arranged to drain onto the casing floor 5, that 25 drains into the tank. The various nozzles are so arranged as to completely and successively envelop the containers in a cloud or fog of spray or atomized liquid, and a cloud or fog of atomized water proofing liquid is 30 approximately present in and around the containers so long as they remain in the spraying chamber even while not in direct alignment with the nozzles and hence the containers are subjected to the soaking effect 35 of this fog or cloud for a more or less extended period while in said chamber; that is, for a greater length of time than it takes each container to pass the position wherein it is in direct alignment with the nozzles. 40 The nozzles 30, 31, are usually arranged somewhat remote from the path traveled by the containers so that the spray will be fully atomized by the time it reaches the containers and will deposit the atoms of liquid 45 throughout the full length of the containers and produce the fog or cloud of vapor that will in effect completely envelop the containers and soak or penetrate the surfaces thereof without resulting in uneven deposit thereon and particularly avoiding the deposit of lumps of paraffining or waterproofing material.

50 The upper nozzle 28, is usually arranged somewhat closer to the containers than the nozzles 30 and 31, so as to deposit an ample supply of waterproofing liquid on the upper ends of the containers to fill the seams or joints between the container bottoms and side walls thereof and if so desired, to spray 55 downwardly along the exterior sides of the containers. The lower nozzle 29, is also usually arranged somewhat close to the lower ends of the containers so that the spray therefrom will thoroughly saturate 60 the complete inner surfaces of the containers

throughout the full lengths thereof as well as the lower end edges of the containers.

Inasmuch as certain types of paper or like-material containers and covers therefor are provided with depressed end closure 70 disks, forming pockets in the exterior ends of such articles, and as these pockets tend to hold and retain an undesirable quantity of the waterproofing liquid deposited therein by the upper nozzle 28, I preferably provide means for expelling the surplus liquid from such pockets before the articles being treated, pass from the spraying or waterproofing chamber. For instance, in the example illustrated, I show an air blast nozzle 75 40, depending in the spraying chamber above the path traveled by the articles *a*, and arranged in advance (in the direction of rotation of the conveyer) of the point where the containers pass between and in 80 alignment with the spraying nozzles. This nozzle is arranged to direct a downward blast of air into said end pocket of each article *a*, to expel the surplus liquid therefrom into the spraying chamber. This air blast 85 40 also serves to hasten the setting and drying of the liquid soaked and impregnated surfaces of said pocket. This air blast nozzle is supplied through air pipe 41, depending through the top wall of the casing, and operatively connected through a suitable valve mechanism with main air supply pipe 42, having cut off valve 43, and extending from 90 any suitable air compressor.

The valve mechanism referred to is preferably arranged to normally maintain the pipe 41, cut off from the supply pipe 42, and to only periodically connect the pipe 41, with supply pipe 42, and hence only periodically permit the discharge of the air blast 100 through nozzle 40. The valve mechanism is so timed that the air blast will be but approximately momentarily established and then only when a container (or other article being treated) is located immediately below the blast nozzle 40. The arrangement is such that each container passing under the nozzle 40, will be subjected to the momentary air blast, the air blast being cut off while each article is moving to and from 110 position in immediate alignment with the nozzle. Various valves or other mechanisms can be provided to thus control the air blast, although in the example illustrated, I show the same timed and controlled by a rotary 115 flat faced disk-like valve 44, rotating between and in closing contact with the aligned otherwise open communicating ends of the pipes 42, 41. This disk is provided with a transverse port 45, adapted to register with 120 said open ends of the pipes and place them in open communication once during each rotation of the disk, but to cut the pipe 41, off from communication with the supply pipe 42, during the remainder of each rota- 125 130

tion. The rotary disk 44, is carried and driven by a shaft 46, mounted in a suitable box on the support 8, and is actuated by gearing 47, connecting said shaft with the 5 power or drive shaft 13, and the gearing 47, so times the rotation of the disk 44, as to establish the air blast only when in the rotation of the conveyer, each article is directly below the blast nozzle.

10 In order to maintain the approximately air tight contact between the end edges of the open ends of the pipes 42, 41, and the side faces of the disk, I preferably grind said edges and the faces of the disk, and 15 yieldingly press the pipe ends to the faces of the disk. For instance, the pipes 41, 42, can be arranged with two approximately-parallel spaced straight laterally-flexible lengths at right angles to the axis of rotation of the 20 disk, and these lengths can terminate in two opposite alined open pipe ends 48, arranged at opposite sides of the disk and parallel with its axis of rotation with the edges surrounding their openings held against the 25 sides of the disk by a retractive spring 49, extending between and joined to said flexible pipe lengths and tending to pull them together.

The containers or other articles being 30 treated pass from the spraying or waterproofing chamber, to the interior of the casing, that is shut off from the spraying chamber by the partitions 26, and the conveyer floor 25, and that constitutes the drying or 35 setting chamber.

The liquid flows down and evenly distributes itself over the container surfaces, and surplus liquid drains and drops therefrom onto the casing bottom 5, while the 40 containers are in the spraying chamber, and in fact possibly this may be taking place after the containers have passed from the spraying chamber into the drying chamber. However, the containers have an extended 45 path of movement through the drying chamber before they reach the discharge c, and while in said chamber the surfaces of the containers become sufficiently dried and set to be delivered therefrom. While in said 50 chamber, the containers are subjected to the heat rising from the hot liquid in the tank 1, and are protected from the vapor fog generated by the spraying nozzles.

As the containers successively arrive beside the discharge opening c, they can be removed by hand from the brackets supporting them and from the casing, but I prefer to automatically discharge the waterproofed 55 containers as the conveyer presents them one at a time beside said discharge opening, and hence avoid contact with human hands, as well as the presence of an operator. Various means can be provided for thus discharging the containers, although in the example illustrated, I utilize an air blast from

an upwardly directed nozzle 50, arranged within the casing and opposite the opening c, and directly under the path traveled by the containers. As each container arrives over this nozzle, an air blast issues therefrom and enters the open lower end of the container and lifts the container upwardly from and entirely free of its supporting bracket, and into engagement with an approximately semi circular deflector 51, which guides the container outwardly through the opening c, and preferably causes the same to drop open end up at the exterior of the casing and onto an upwardly moving conveyer 52, forming the traveling floor of a 80 trough 53, in which the containers can be carried to any suitable location for storage or further operations.

The deflector 51, is preferably so arranged with respect to the path of the containers 85 in the casing and the opening c, and is so curved as to cause the containers to make a half turn while moving from the rotary conveyer to the offtake trough. The deflector 51, can consist of a curved plate extending into 90 the casing through the upper end of opening c, and adjustably and removably supported by a bracket 54, secured to the exterior of the casing.

The air blast nozzle 50, is preferably supplied with air under pressure from pipe 41, through the pipe 55, which forms a branch of pipe 41, and hence the blast is periodically established through disk 44, as herein-before described, so that the container discharging blast will be momentarily established only when a container moves into alinement therewith, and simultaneously with the establishment of the surplus-liquid-expelling blast through nozzle 40, 105 although my invention is not so limited.

If so desired, the traveling conveyer floor 52, can be driven from shaft 13, through the medium of suitable pulleys and a connecting belt and a shaft carrying the lower drum of 110 the said conveyer.

If so desired, a guard flange 56, can be provided within the casing immediately above the opening b, to protect the hand of the operator when placing containers on the brackets of the rotary conveyer, from hot waterproofing liquid that might drop from the top wall of the casing.

The continuous rotary travel of the articles to be treated, can be around a horizontal axis, if so desired, instead of around a vertical axis, and many other variations, modifications and rearrangements can be resorted to without departing from the spirit and scope of my invention as defined by the hereinafter recited claims. For instance, in Fig. 5, I diagrammatically and partially illustrate, an apparatus, wherein the rotary conveyer 18^a, for the articles a, to be treated by liquid from the tank 1^a, is mounted on 120 125 130

and rotates about the horizontal axis 7^a, driven through the medium of any suitable gearing, involving for instance, suitably driven shaft 12^a, and gearing 10^a. The waterproofing liquid in tank 1^a, can be kept at the desired temperature by any suitable means, such for instance, as hereinbefore suggested in describing tank 1. An upright or vertically arranged box or casing 3^a, is 10 mounted on the tank 1^a, with its interior draining thereinto, and the vertically rotating conveyer 18^a, is inclosed within said casing, and carries the articles *a*, in a vertical circular path therein and between various spraying nozzles 28', 29', 30', 31', arranged as hereinbefore described, and supplied with liquid from the tank 1^a, as hereinbefore described. The continuously rotating conveyer 18^a, is provided with inclined 15 upright arms for maintaining the containers, or other articles to be liquid treated, in upright inverted position as hereinbefore described. These arms in the construction of Fig. 5, are preferably carried by weighted 20 brackets 20^a, hung from and rotatably mounted on horizontal studs 20^b, projecting laterally from the rim of the rotary conveyer 18^a. These brackets are so mounted 25 on the studs, as to always hang vertically therefrom by gravity; as the conveyer rotates, to maintain the containers *a*, in vertical 30 position.

Any suitable means (not shown) can be provided for automatically discharging the 35 containers from the arms after the containers have been waterproofed and dried, and also the casing is provided with an opening (not shown) through which the containers to be treated can be placed on the 40 arms.

It is evident that modifications and departures can be resorted to without departing from the spirit and scope of my invention and hence I do not wish to limit myself 45 to the disclosures hereof.

Desiring to protect my invention as broadly as is legally possible, what I claim is:—

1. In apparatus for treating paper or 50 other material containers with liquid, means for carrying said articles with their inner and outer surfaces exposed to receive sprayed or atomized liquid, and liquid spraying or atomizing devices arranged for spraying both the inner and outer surfaces 55 of said articles with liquid as said articles are transported by said means.

2. In combination, means providing a 60 chamber, heating means for said chamber, devices for maintaining a fog or cloud of atomized liquid therein, and a conveyer provided with means for maintaining paper material containers or the like in inverted position for draining and with their exterior 65 and interior surfaces exposed to said fog and

for transporting said containers through said chamber.

3. In combination, a casing including means providing a chamber, devices for maintaining a fog or cloud of atomized waterproofing liquid in said chamber, and a table arranged in said casing and rotating on a center axis and provided with an endless series of holders for receiving and continuously moving series of paper material containers or the like through said chamber and exposing the surfaces thereof to the waterproofing action of said atomized liquid and within said casing for draining. 70 75

4. In combination, a casing providing a chamber, devices for maintaining a fog or cloud of atomized waterproofing liquid in said chamber, and a continuously rotating conveyer arranged within said casing and provided with means for holding paper material articles and for passing the same through said chamber and exposing the surfaces thereof to said atomized liquid, said casing provided with adjacent inlet and discharge openings to said conveyer whereby a single operator can supply articles to said conveyer and observe the discharge of articles therefrom. 85 90

5. In combination, means providing a liquid spraying chamber and a drying chamber, and a continuously moving conveyer provided with means for individually holding paper containers and the like and for passing them successively through said spraying chamber and said drying chamber, said means provided with a container inlet opening to said conveyer and adjacent to said spraying chamber, and also provided with a container discharge opening from said drying chamber and adjacent to said inlet opening, substantially as described. 95 100 105

6. In combination, a conveyer provided with devices for individually receiving and holding paper containers and the like in inverted position with their inner and outer surfaces exposed to the action of liquid spraying devices, and spraying nozzles to spray the interiors and the exteriors of said containers. 110

7. In combination, a continuously rotating 115 endless conveyer provided with an endless series of uniformly spaced individual paper material container holders, a casing in which said holders travel, heating means, and vertically and horizontally arranged liquid spraying devices for spraying said containers, said means being arranged to heat the interior of said casing, substantially as described. 120 125

8. In combination, a liquid pot or tank, a casing arranged thereon and draining thereinto, means for heating said pot and the interior of said casing, liquid spraying devices, means to force liquid from the tank and to said devices, and an endless conveyer within 130

- said casing for transporting paper material containers or the like in said casing and through the spray delivered by said devices.
9. In combination, a casing, liquid spraying devices arranged to deliver sprays of atomized waterproofing liquid or the like in said casing, means to supply said devices with waterproofing liquid or the like under pressure, means for maintaining said liquid in a heated condition and for heating the interior of said casing, and a conveyer for passing paper material containers and the like through said sprays and thereafter along an extended path of movement within said casing for draining, said conveyer provided with an endless series of means for holding containers in vertical position.
10. In combination, liquid spraying devices, means for holding in inverted position and successively passing paper material containers or the like through the spray generated by said devices, a casing inclosing said means and the containers carried thereby, and heating means for said casing, said means and the casing providing an extended path of movement for the containers after leaving said devices for draining and drying the containers.
11. In combination, vertically and horizontally directed liquid sprayers for subjecting the inner and outer surfaces of paper containers and the like, to water-proofing liquid, and a continuously moving endless series of holders for said containers arranged to pass the containers individually within range of action of said sprayers, and having an extended path of movement beyond the sprayers for allowing the containers to drain and dry.
12. Means for holding containers individually in inverted position with their open ends exposed, and mechanism for simultaneously spraying said containers through their open ends and at their outer surfaces with waterproofing material, substantially as described.
13. In combination, means for transporting containers along an extended path of movement and for holding the same in inverted position with their inner and outer surfaces exposed while being so transported, and devices near the front end of said path of movement for spraying the inner and outer surfaces of said containers with waterproofing liquid or the like.
14. In combination, a continuously moving conveyer rotating around a central axis and provided with an endless series of individual container holders, a casing providing a drying and draining chamber through which said holders travel, said casing having an inlet opening for passage of containers to said holders and an exit opening adjacent to said inlet opening for discharge of containers from said holders and spraying devices for subjecting the containers carried by said holders to sprayed waterproofing liquid before said containers enter said chamber.
15. In combination, means for transporting paper material containers and the like along an extended path of movement while maintaining them inverted, spraying devices for subjecting said containers to sprayed waterproofing liquid at the beginning of said extended path of movement, means for heating said liquid, and a casing in which said containers travel while being sprayed and which provides a drying chamber through which said extended path of movement extends.
16. In combination, means for holding in inverted position and transporting paper material containers and the like along an extended path of movement, devices for spraying the containers with waterproofing liquid or the like while moving along said path, and means for expelling surplus liquid from each container.
17. In combination, means for transporting paper material containers and the like, means for spraying the inner and outer surfaces of said containers with a waterproofing liquid while being transported and means for removing surplus liquid from the ends of such containers, and transporting means holding the containers in upright position for draining.
18. In combination, a rotary table for transporting paper material containers and the like, along an extended circular path of movement and for holding said containers while being transported, means for subjecting said containers to waterproofing liquid or the like while being transported, a casing in which the table is inclosed having adjacent container inlet and outlet openings, and means for automatically and successively discharging said containers from said transporting means as said containers reach the end of said path of movement.
19. In combination, means for transporting paper material containers and the like along an extended path of movement and for maintaining them in inverted position while being transported, devices for subjecting said containers to waterproofing liquid while being transported, and means for directing an upward air blast into each container as it reaches the end of said path of movement to discharge said container from said transporting means.
20. In combination, means for transporting paper material containers and the like along a fixed path of movement and for maintaining them loosely and by gravity in upright positions while being transported, means for treating said containers with waterproofing liquid, and devices for automatically discharging said containers from said transporting means as they successively

reach the end of said path of movement and for delivering the same in reverse upright positions comprising an air blast nozzle below said path of movement and a curved 5 deflector above said path of movement, substantially as described.

21. In combination, means for transporting containers along a fixed path of movement and for maintaining them in vertical 10 inverted position while being transported, devices for treating the surfaces of said containers to liquid while being transported, and an air blast device arranged above said path of movement for directing a downward 15 air blast against the top of each container after it has been treated to liquid for expelling surplus liquid from the top ends thereof.

22. In combination, a rotating conveyer 20 provided with an endless series of individual paper container holders, and liquid spraying nozzles arranged above, below, and on opposite sides of the path traveled by said holders and arranged to direct liquid 25 sprays against the interior and exterior side and end surfaces of the containers while being transported by said conveyer.

23. In combination, a table rotating continuously about a fixed center and provided 30 with an endless series of uniformly spaced container holders arranged beyond its periphery, and liquid spraying nozzles arranged to direct liquid sprays into the path traveled by the containers being transported 35 by said holders, from approximately all directions to subject the complete inner and outer surfaces of each container to liquid spray.

24. In combination, an approximately annular casing, a table rotating therein about a center axis and provided with a continuous series of uniformly spaced container holders arranged beyond the periphery of the table and traveling in an extended path 45 of movement in said casing from an inlet opening through the wall of said casing to a discharge opening for containers through the wall of said casing, and means providing a liquid treating chamber in said casing and 50 arranged near the beginning of said path of movement and through which said containers successively pass to be liquid treated.

25. In combination, an open bottom casing having an inlet opening, an adjacent 55 discharge, a rotary conveyer provided with an endless series of individual container holders successively movable in said casing along an extended circular path from said inlet to said discharge, a liquid pot below 60 said open bottom of the casing and said circular path and means near the front end of said path for subjecting the inner and outer surfaces of the advancing containers to liquid spray, the remainder of said path

within the casing to said discharge being 65 provided for draining and drying the containers.

26. In combination, a liquid tank provided with means for heating the liquid therein, a casing arranged thereover and draining and opening therein and subjected to the heat rising therefrom, said casing having a container inlet and a container discharge, a rotary conveyer moving around a center axis and arranged to simultaneously 75 carry, drain and dry a multiplicity of containers while transporting them along an extended circular path of movement within the casing from said inlet to said discharge and to successively receive containers at 80 said inlet and to successively discharge containers at said discharge, and mechanism for spraying the surfaces of said containers with liquid from said tank while said containers are being transported along said 85 path.

27. In combination, a casing having a container inlet and an adjacent container outlet, a table rotating about a center axis and provided with an endless series of individual container holders carried thereby in an extended path in said casing from 90 said inlet to said outlet, means within said casing providing a liquid spraying chamber through which the front portion of said path extends to subject the containers advancing along said path to the spray in said chamber, and oppositely arranged nozzles for spraying liquid in said chamber and enveloping the containers therein. 100

28. In apparatus for paraffining paper containers and the like, a paraffin pot provided with heating means, an open-bottom casing over said pot, a container conveyer in said casing and rotating on a center 105 axis, said casing having an inlet and an adjacent outlet, nozzles, and a pump for driving the liquid paraffin from the pot and discharging the same through said nozzles on to containers carried by said conveyer. 110

29. In apparatus for paraffining paper containers and the like, in combination, a paraffin pot provided with heating means, a casing forming a chamber over said pot, means for discharging liquid paraffin vertically and horizontally into said chamber in the form of spray and for drawing said paraffin from said pot, and holders for maintaining containers in the casing with their inner and outer surfaces exposed and 115 subject to said spray.

30. In apparatus for paraffining paper containers and the like, in combination, means for discharging hot liquid paraffin vertically and horizontally in the form of 125 spray, and mechanism for conveying paper containers through said spray and exposing the inner and outer surfaces thereof to said

spray while said containers are held vertically for draining.

31. In apparatus for paraffining paper containers and the like, in combination, means for discharging hot liquid paraffin in the form of spray over the complete inner and outer surfaces of containers, and mechanisms for conveying paper containers and subjecting said surfaces thereof to said spray and for then moving said containers along an extended path of movement for draining and drying.

32. In apparatus for treating the surfaces of paper containers and the like with liquid, in combination, a conveyer provided with means for receiving and carrying forward a multiplicity of spaced containers, means for treating the surfaces thereof with liquid while said containers are being moved forward by said conveyer, means for subjecting surfaces of said containers to an air blast, and valve mechanism for periodically

cally establishing and cutting off said air blast.

33. In apparatus for treating the surfaces of paper containers and the like with liquid, in combination, a constantly rotating conveyer provided with uniformly spaced container holders, means for treating the surfaces of the containers with liquid while the containers are being advanced by said conveyer, air blast nozzles arranged above and below the path along which said conveyers move, and automatic valve mechanism for periodically and simultaneously directing air blasts through said nozzles and against said conveyers.

In testimony whereof I affix my signature in the presence of two witnesses.

WILBUR L. WRIGHT.
